Des. 1484

Henry H. Watchkiss, of Bristol, Conn.
Attest No. 1484. Letters Patent No. 119, dated Oct. 29, 1861.

The schedule referred to in these Letters Patent and making part of the same.

To all whom it may concern:

Be it known that, Henry H. Watchkiss, of Bristol, County of Hartford and State of Connecticut, have invented or produced a new and original design, or pattern, for a Clock Case, and I do hereby declare that the following is a full and exact description of the same, reference being had to the photographic views, in which the same letters indicate like parts.

In the accompanying photographic views is shown a new and original design, or pattern for a clock case.

A. are straight flat sides and rounded top.

B. is a rounded, or oval configuration on the front edge of the case.

C. is a plain edge base.

The three combined to produce a plain rich design, or pattern for a clock case.

What I claim therefore and desire to secure by Letters Patent, is. The design or pattern for a Clock Case as hereinbefore illustrated and described.

In testimony whereof, I have hereunto set my hand and seal this 7th day of September 1861.

Witnesses.
